United States Patent

Des. 236,206

Patented Aug. 5, 1975

236,206

TOILET

Charles W. McHose, Hawthorne, Calif., assignor to Thetford Corporation, Ann Arbor, Mich.

Filed Dec. 19, 1973, Ser. No. 426,430

Term of patent 14 years

Int. Cl. D23—02

U.S. Cl. D23—67

—FIG. 1

—FIG. 2

FIG. 1 is a perspective view of a toilet showing my new design;

FIG. 2 is another perspective view thereof showing the cover in an elevated position;

FIG. 3 is a top plan view of FIG. 1;

FIG. 4 is a front elevational view of FIG. 1;

FIG. 5 is a left side elevational view of FIG. 1;

FIG. 6 is a right side elevational view of FIG. 1; and

FIG. 7 is a rear elevational view of FIG. 1.

I claim:

The ornamental design for a toilet, as shown.
